UNITED STATES PATENT OFFICE.

HERMAN NEUWIRTH AND JACOB BERNSTEIN, OF BROOKLYN, NEW YORK.

DESIGN FOR A HEATER FOR SHAPING EYEGLASS FRAMES.

Application filed December 13, 1923. Serial No. 8,017. Term of patent 14 years.

To all whom it may concern:

Be it known that we, HERMAN NEUWIRTH and JACOB BERNSTEIN, citizens of the United States, residing in the borough of Brooklyn, city and State of New York, have jointly invented a new, original, and ornamental Design for a Heater for Shaping Eyeglass Frames, of which the following is a specification, reference being had to the accompanying drawing, forming part hereof.

Figure 1 is a plan view and

Figure 2 is an elevation of a heater for shaping eyeglass frames showing our new design.

We claim:

The ornamental design for a heater for shaping eyeglass frames, as shown.

HERMAN NEUWIRTH.
JACOB BERNSTEIN.
